PACKING RETAINER FOR JOURNAL BOXES

Charles T. Ripley, Wilmette, Ill.

Application July 2, 1936, Serial No. 88,601

4 Claims. (Cl. 308—89)

This invention relates to journal boxes of the type used on railway cars in which a packing is disposed in the box under the journal for keeping the journal lubricated.

The object of the invention is to provide an efficient and inexpensive device, which can be readily put into and taken out of the journal box, for keeping the packing in its proper place.

The device of the invention is intended particularly for use with journal box packings in which the waste and the springs interwoven with the waste (when the latter are used) are enclosed in a cloth envelope or envelopes as disclosed in application of the present applicant filed January 25, 1935, Serial No. 3433 (U. S. Patent 2,049,225, July 28, 1936); and in such case the device serves not only as an aid in holding the packing element or elements against the under side of the journal—aiding the springs, which are distributed through the waste, in this respect—but prevents the flange or rib on the outer end of the journal from cutting or wearing the envelope.

The device, however, might be used to advantage in arrangements where the packing was not enclosed in an envelope or envelopes. In such case the device would help to maintain the packing in its proper position and prevent it from working out into the front of the box and rolling out of place particularly in cold weather when the oil is sticky.

The invention is illustrated in a preferred embodiment in the accompanying drawing in which Fig. 1 is a longitudinal view of a railway car journal and journal box, the latter provided with the packing retainer of the present invention.

Fig. 2 is a sectional view on line 2—2 of Fig. 1, and

Fig. 3 is a view in perspective of the packing retainer.

The journal box as shown in the drawing is of a common type. The body of the box is shown at 10 and the cover at 11. The journal 12 is formed with the usual end flange 13. 14 represents the brass and 15 the wedge which is ordinarily formed with an opening 16 for convenience in removing the wedge from the box when the brass is to be replaced or repaired. The main body of packing, which preferably consists of cotton or wool waste 17 and coil springs 18 distributed therein and interwoven therewith, is enclosed in a soft and oil porous envelope 19 and is arranged under the journal 12 with the outer end of the envelope bearing against the end flange 13 of the journal. Arranged in the portion 55 of the journal box outwardly of the journal is

a body of waste 20 and it is against this body or plug of waste that the packing retainer of the present invention is intended to bear so as to produce an end thrust against the main packing element arranged under the journal. The fact that the under-portion of the journal box below the opening into the box is sloped or rounded, as indicated at 21, aids in transmission of the downward thrust on the plug 20 into an end thrust against the main body of packing 17. 5 The spring retainer for accomplishing this purpose consists preferably of a spring wire 22 bent to form legs 23, 23, preferably provided with loops 24, 24 to increase the resiliency of the legs. The legs 23 are connected by a cross piece 25, the 10 middle portion 26 of which is preferably offset so as to give an effectively wider bearing of the device on the plug of packing 20. The wire 22 is formed with angular end portions 27, 27 which are adapted to extend into the opening 16 in wedge 15. The device is proportioned so that it has to be sprung into place between the wedge and the packing 20. That is, in this operative position it is under very considerable spring pressure. 15

By means of this device the end of the envelope 19 adjacent the flange 13 of the journal, is prevented from overlapping the flange and being cut or worn by the rotation of the journal. The packing retainer also tends to keep the main body of packing 17, whether enclosed in an envelope or not, in contact with the journal thereby increasing the efficiency of the packing as means for transmitting lubricant to the journal. In cases particularly of packing not inclosed in an envelope the retainer keeps the packing in place and prevents it from working out toward the front end of the box and rolling with the journal. 30 35

The spring retainer is interlocked with a non-rotary portion of the journal box assembly (the wedge in the present example) so that it cannot be rotated or displaced by movements of the journal or packing material. The retainer will not be disturbed by the opening or closing of the lid 11, and is so shaped and positioned as not 40 45 to interfere with the oiling of the packing. However, the retainer may be easily removed by flexing the legs and snapping the ends out of interlocked engagement with the wedge, if the packing material is to be removed or replaced. 50

The intention is to claim all variations and modifications of the devices and combinations disclosed within the scope of the appended claims.

I claim:

1. In combination with a journal box, journal,

- 5 brass and wedge, the latter formed with an opening in its outer end: a lubricating packing in the box under the journal; a body of packing bearing against the aforesaid packing and extending beyond the end of the journal; and a spring packing retainer comprising a spring wire, the ends of which are engaged in the opening in the wedge and the middle portion of which bears against said second-named body of packing.
- 10 2. In combination with a journal box, journal, brass and wedge, the latter formed with an opening in its outer end: a lubricating packing in the box under and extending outwardly beyond the end of the journal; and a packing retainer consisting of a spring wire bent to form legs, a middle portion to bear against the packing and end portion to enter the opening in said wedge.
- 15 3. In combination with a journal box, journal, brass and wedge, the latter formed with an opening in its outer end: a lubricating packing in the

box under and extending outwardly beyond the end of the journal; and a packing retainer consisting of a spring wire bent to form legs formed with spring loops, a middle portion to bear against the packing and end portions to enter 5 the opening in said wedge.

4. In combination with a journal box, journal provided with an end flange, brass and wedge, the latter formed with an opening in its outer end: a lubricating packing in the box under the 10 journal and contained in one or more envelopes: a body of packing bearing against the aforesaid packing and extending beyond the end of the journal: and a packing retainer consisting of a wire bent to form spring legs, an offset middle 15 portion to bear against said last-named body of packing and end portions to enter the opening in the wedge.

CHARLES T. RIPLEY. 20
